UNITED STATES PATENT OFFICE

119,679

DESIGN FOR A TEXTILE FABRIC

Harry Rubin, New York, N. Y.

Application February 8, 1940, Serial No. 90,140

Term of patent 7 years

To all whom it may concern:

Be it known that I, Harry Rubin, a citizen of the United States of America, residing at New York, in the county of New York and State of New York, have invented a new, original, and ornamental Design for a Textile Fabric, of which the following is a specification, reference being had to the accompanying drawing, forming part thereof, and in which:

I claim:

The ornamental design for a textile fabric, substantially as shown.

HARRY RUBIN.
